UNITED STATES PATENT OFFICE

JAMES JOSEPH SHIELDS, OF GUELPH, ONTARIO, CANADA

GATE OPERATING AND LOCKING MECHANISM

Application filed July 15, 1927. Serial No. 205,983.

This invention relates to certain improvements in gate operating and locking mechanisms, and has relation more particularly to a mechanism of this general character especially designed and adapted for use in connection with double doors, and it is an object of the invention to provide such a mechanism having novel and improved means whereby the doors may be caused to operate in unison together with means for effectively holding or locking said doors when either in open or closed position, as hereinafter more particularly explained.

Fig. 1, is a plan view of my invention showing the doors locked closed, and showing part of the door frame in section. Fig. 2, is a view similar to Fig. 1, but showing the doors locked open. Fig. 3, is a cross section on the line 3—3, Fig. 1. Fig. 4, is an elevation of the inner side of one of the doors showing how the door handle is connected with the lock-operating means. Fig. 5, is an elevation of the outer side of one of the doors showing how the door handle is padlocked or otherwise secured against unauthorized movement. Fig. 6, is an edge view of one of the doors showing both parts of the handle for the door, in side elevation, and Fig. 7, is a detail showing how the guide-bar for the latch carriage, is supported.

In the drawings, like letters of reference refer to the same parts.

The door-frame 2, may be of any desired construction, and suitably hinged thereto are the doors 3, which preferably open outwardly. 4, is the guide-bar, and the same may be supported in any suitable manner; I have shown its inner end attached to part of the door-frame 2, and its outer end is attached to any suitable part of the building, such as a scantling 5. Mounted to move longitudinally on the guide-bar 4, is a carriage 6, to which is pivoted the latch 7, as by means of the stud or pin 8. (See Fig. 3.) This latch is provided with upper side flanges 9, which ride upon the said guide-bar, and at one end on its lower side it is provided with flanges 10 which engage the under side of said guide-bar. These flanges keep the said carriage in cooperative relationship with said

guide-bar and permit of the freedom of movement to said carriage. But it must be understood that I do not confine myself to any specific construction of carriage that will function as I desire.

Integrally formed with each side of the carriage 6, are ears 11, in which are supported the inner ends of the thrust-rod 12. The outer ends of these thrust-rod are movably coupled to the doors 3, as by screw-eyes 13, 60 or equivalent means.

In Fig. 1, the notch 15, of the latch 7, is shown in engagement with the pin 14, carried by the guide-bar 4; this pin is located at the limit of the inward movement of the carriage 6, and when the said notch 15, is in engagement therewith, the carriage 6, is locked, and consequently the doors 3, are locked. To unlock the said carriage from the guide-bar 2, the latch 7, is moved on 70 its pivot pin or stud 8 to move the notch 15, out of engagement with the pin 14. The said latch must be held in this position so as to allow the carriage to be moved outwardly. While I may use any suitable means to move the said latch as described, I prefer to use the following means, because thereby I am enabled to dispense with the ordinary locking means now almost universally used and which consists of two members, one being carried by one door, and the other by the other door. Mounted by means

of a spindle 16, in one of the doors, are the members of the door handle, 17, and 18. These members may be of any suitable form or shape, but I prefer to form them so that the hand will enter same, as shown. Carried by the member 18, is an ear 19, to which one end of the flexible member 20, is connected. This flexible member is passed through an eyelet 21, carried by one of the doors, and its inner end is attached to the tail 22, of the latch 7. When the member 18, is turned on its spindle 16, the flexible member 20, is moved so as to retract the 90 notch from engagement with the pin 14. While the member 18, is held in its turned position, the operator pulls on same thereby moving the carriage 6 outwardly along the guide-bar 4. This movement of the said 100

carriage will cause the thrust-rods 12, to exert pressure against the doors and cause them to open. When the doors are fully open, the carriage 6 will contact with the pin 23, carried by the guide-bar, and when the turning force exerted by the hand against the member 18, is removed, the spring 24, will move the latch 7, back to normal position at which time the notch 25, of the said latch will engage with the pin 23, and so hold the doors locked in open position.

The member 18, is on the inside of its associated door, while the member 17, is on the outside. Since these members are connected together by the spindle 16, the movement of one is the same as the movement of the other. When the doors are to be closed, naturally the hand grasps the member 17, and by turning same the latch 7, is disengaged from the pin 23, and as pushing pressure is applied to one of the doors, the said latch is ultimately caused to engage with the pin 14, and so lock the doors closed.

Carried by the door supporting the members 17, and 18, is an eye 26, with which matches an ear 27, carried by the member 17; this eye limits the movement of the members 17, and 18, in one direction so as to prevent any overthrow to the latch 7, which would cause its disengagement with the pins 14, and 23.

Carried by the stud or pin 8, at one end, is the spring 24. As shown, this spring is coiled around said stud or pin, and the other end is placed to rest against the tail 22, of the latch 7. Energy stored in the said spring will move the said latch when this latter is not dominated by force exerted by the flexible member 20.

A stop 28, preferably formed by bending down portion of the latch 7, must be provided; this stop comes in contact with the side of the carriage 6, (see Figs. 1, and 2), and so limits the movement given the said latch under the influence of the spring 24. The result is that the necessary movements can be given the said latch by the members 17, and 18.

A padlock, for instance, may be associated with the ear 27, and eye 26 so as to positively lock the mechanism hereinbefore described against operation.

The contrivance herein described is sturdy in construction, and consists of the minimum number of parts to effect the purpose desired.

I do not confine myself to the details of construction described and shown which can be altered or changed without departing from the principle of my invention.

What I claim as my invention is:—

1. A latching means comprising a carriage adapted to be mounted to slide longitudinally on a horizontal bar; an ear at each side of

said carriage; an integrally formed spring-controlled horizontally disposed latch member pivoted to said carriage to normally occupy a position longitudinally thereof and provided with oppositely faced hooks between which is located the pivotal point for said latch, and a stop carried by said latch for engagement with said carriage.

2. In a latching means as set forth in claim 1, the provision of top and bottom flanges for said carriage which have sliding contact with said bar.

3. In a latching means, the combination with a horizontal bar, and a pin carried by each end of said bar and projecting above the top side thereof, of a latching means comprising a carriage adapted to be mounted on the said bar for longitudinal movement thereon; an integrally formed spring-controlled horizontally disposed latch member pivoted to said carriage and provided with oppositely faced hooks between which is located the pivotal point for said latch; means for moving said carriage longitudinally on said bar to cause said hooks to alternately engage said pins; means for moving said latch so as to bring the engaged hook out of engagement with its associated pin, and a stop carried by said latch for engagement with said carriage.
